UNITED STATES PATENT OFFICE.

ALBERT E. CRANSTON, OF SPOKANE, WASHINGTON.

MECHANICAL MOVEMENT.

1,417,503.

Specification of Letters Patent. Patented May 30, 1922.

Application filed March 28, 1921. Serial No. 456,418.

To all whom it may concern:

Be it known that I, ALBERT E. CRANSTON, a citizen of the United States, and a resident of Spokane, in the county of Spokane and 5 State of Washington, have invented certain new and useful Improvements in Mechanical Movements, of which the following is a specification.

My invention relates to improvements in 10 mechanical movements and has for its principal object to provide a simple and efficient device for converting reciprocating and reversing rotary movement into continuous rotatory movement.

15 A further object is to provide a device of the class described which shall employ no ratchets, springs or pawls and thereby eliminate the expense and wear and tear of such elements.

20 A further object is to provide a device of the class described which may be manufactured cheaply and yet be readily convertible for a multitude of uses. For example, it may advantageously be used in connection 25 with wrenches or drills as a substitute for the usual ratchets. When used in this manner there is no idling stroke, but each stroke is a work stroke, hence causing the tool to do twice as much work as would an ordinary 30 ratchet wrench or drill.

Other objects and features of novelty will be described in connection with the accompanying drawings and specifications and more particularly pointed out in and by the 35 appended claims.

In the drawings:

Figure 1 is a side elevation of the improvement.

Figure 2 is a plan view of the same

40 Figure 3 is an enlarged section on line 3—3 of Figure 1.

Figure 4 is a section on line 4—4 of Figure 3.

45 Figure 5 is a section through the housing of the improvement but showing the interior mechanism in elevation.

Figure 6 is a view similar to Figure 5, but showing the mechanism in a different position.

50 Figure 7 is a view similar to Figure 5, but showing the mechanism in a position different to that of Figure 5 or Figure 6.

Like numerals of reference designate the same part throughout the various figures 55 of the drawings.

The shaft 10 which is to be driven has

secured thereto by pin 11 the member 12 which comprises a bevel gear. The housing 13 encloses gear 12 and is provided with a handle 14 which may be termed a holding 60 handle. During the operation of the improvement handle 14 is held stationary and also serves to enable the operator to steady the device. In the case of a permanent installation handle 14 or the housing 13 may be 65 rigidly fastened in non-movable position.

Threaded through the housing 13 are the pins 14 which serve as bearings for the bevel pinions 15 which mesh with bevel gear 12. Rotatably mounted on shaft 10 is the intermediate member 16, the lower surface of which is cut to form bevel gear teeth 17 adapted to mesh with bevel pinions 15. The upper surface of member 16 is cut to form engagement teeth 18. The driven member 75 19 is secured to shaft 10 as by pin 20 and is provided on its lower surface with engagement teeth 21. In order to keep gear 16 in mesh with pinions 15 and to separate members 16 and 19 by a pre-determined distance, 80 I have provided the spacing sleeve 22, which may be either tight or loose on shaft 10. In the present disclosure I have shown the ends 23 and 24 and bearing against the bottom of counter bores 25 and 26, respectively, but 85 it will be understood that any of the usual collar means may be substituted for sleeve 22 in order to allow member 16 to revolve on shaft 10 and yet be kept in mesh with pinions 15. 90

Disposed between members 21 and 16 is the driving member 27 which is rotatably and slidably mounted with respect to shaft 10.

On the upper face of member 27 are provided the engagement teeth 28 registering 95 with teeth 21 and on the lower side thereof are the engagement teeth 29 registering with teeth 18. As a convenient means for rotating driving member 27 I have provided the collar 30 secured to member 27 by such 100 means as screw 31 and adapted to be rotated by handle 32.

Assuming that the parts be in the position of Figure 5, and handle 32 and hence driving member be rotated in the direction of 105 arrow "a" or counter-clockwise, it will be noted that teeth 21 and 28 are out of engagement. Teeth 29 and 18 being in engagement, member 16 will be driven in a counter-clockwise direction and, through 110 the medium of pinions 15 will drive gear 12 in a clockwise direction. Gear 12 being

pinned to shaft 10 at 11, shaft 10 will also be driven in a clockwise direction. When the direction of rotation of handle 32 and driving member is changed to clockwise movement, the action shown in Figure 6 will take place. The member 27 being revolved in a clockwise direction will cause the teeth 29 to ride upwardly or back off of teeth 18 and this movement results in teeth 28 riding upwardly into engagement with teeth 21. It might be supposed that if the faces "c" of teeth 28 were to strike faces "d" of teeth 21 before teeth 29 had entirely backed away from teeth 18 that a lock would result, but such is not the case since the moment faces "c" contact with faces "d" member 19 will be driven in a clockwise direction (Figure 7) carrying with it the shaft 10 and gear 12, since both member 19 and gear 12 are pinned to shaft 10. Gear 12 in turning clockwise will, through pinions 15, turn intermediate member 16 in a counterclockwise direction and thus aid in thrusting teeth 29 upwardly until they clear teeth 18. Thus, the shaft 10 is being revolved in a clockwise direction through the direct drive between member 27 and member 19, or in the same direction as during the first operation described.

Upon again changing the direction of rotation of handle 32 and member 27. (dotted arrows, Figure 6) teeth 28 will back off of teeth 21 and thereby urge teeth 29 into engagement with teeth 18 until the parts are again in the position of Figure 5 whereupon the continued rotation of member 27 will revolve shaft 10 in a clockwise direction.

To cause shaft 10 to revolve in a counterclockwise direction, the device may be turned upside down, handle 32 still being used as a work handle and 14 used as a holding handle.

The ends of shaft 10 may be squared as at 10' or otherwise mutilated or arranged for the attachment of tools or power transmission devices.

If handle 32 be used as a crank connected to a reciprocating rod "A" as shown in dotted lines Figure 2, it will be seen that reciprocal movement on the part of rod "A" will be converted into constant rotary movement on the part of shaft 10.

While I have herein shown and described one specific embodiment of my invention, I do not wish to be limited thereto except for such limitations as the claims may impart.

I claim:

1. A mechanical movement comprising a shaft to be driven, a driving member rotatably mounted on said shaft and slidable with respect thereto; a driven member secured to said shaft and adapted to be directly driven by said driving member only when said driving member is rotated in one direction, a third member secured to said shaft, an in-

termediate member rotatably mounted on said shaft and adapted to be driven by said driving member only when said driving member is rotated in the opposite direction, means operatively connecting said intermediate and said third members whereby their direction of rotation is opposite when said shaft or said intermediate member is rotated.

2. A mechanical movement comprising a shaft to be driven a driving member rotatably mounted on said shaft and slidable with respect thereto, a driven member secured to said shaft on one side of said driving member, a third member secured to said shaft on the other side of said member, an intermediate member rotatably mounted on said shaft and positioned between said driving and said third members, means operatively connecting said intermediate and said third members whereby their direction of rotation is opposite, and co-acting means on said driving, driven and intermediate members whereby a change in the direction of rotation of said driving member causes said driving member to slide on said shaft out of driving engagement with said driven member and into driving engagement with said intermediate member or vice versa.

3. A mechanical movement comprising a shaft, a member secured to said shaft, engagement teeth on said member, an intermediate member rotatably mounted on said shaft, engagement teeth on said intermediate member, a driving member rotatably mounted on said shaft, engagement teeth on one surface of said driving member adapted to engage the teeth on said first mentioned member, engagement teeth on another surface of said driving member adapted to engage the teeth on said intermediate member and means co-acting with said intermediate member and said shaft whereby a change in direction of rotation of said driving member causes said driving member to slide on said shaft whereby the engagement teeth on said driving member are thrown into engagement with the teeth of either one of said first mentioned or intermediate members and out of engagement with the teeth of the other.

4. A mechanical movement comprising a shaft, a member reamed to said shaft, engagement teeth on said member, an intermediate member rotatably mounted on said shaft, engagement teeth on said intermediate member, a driving member rotatably mounted on said shaft, engagement teeth on one surface of said driving member adapted to engage the teeth on said first mentioned member, engagement teeth on another surface of said driving member adapted to engage the teeth on said intermediate member and means co-acting with said intermediate member and said shaft whereby a change in direction of rotation of said driving member

causes said driving member to slide on said shaft whereby the engagement teeth on said driving member are thrown into engagement with the teeth of either one of said first mentioned or intermediate members and out of engagement with the teeth of the other, said means comprising a gear secured to said shaft and an operative connection between said gear and said intermediate member whereby their direction of rotation is opposite.

5. A mechanical movement comprising a shaft to be driven, a driven member secured to said shaft, engagement teeth on said member, a driving member rotatably mounted on said shaft, an intermediate member rotatably mounted on said shaft, teeth on said

intermediate member, teeth on said driving member adapted to engage with the teeth on said driven member when said driving 20 member is rotated in one direction, teeth on said driving member adapted to engage with the teeth on said intermediate member when said driving member is rotated in the opposite direction, a bevel gear rotatably mounted on said shaft but fixed to said intermediate member, a bevel gear secured to said shaft, a housing, bevel pinion journaled on said housing and meshing with said bevel gears.

15 In testimony whereof I hereby affix my signature.

ALBERT E. CRANSTON.
